Primary Examiner — Ruth McInroy(74) *Attorney, Agent, or Firm* — Greenberg Traurig, LLP(57) **CLAIM**

I claim the ornamental design for a vacuum base, as shown and described.

DESCRIPTION

FIG. 1 is a front perspective view of our vacuum base;
 FIG. 2 is a front view thereof;
 FIG. 3 is a rear view thereof;
 FIG. 4 is a left side view thereof;
 FIG. 5 is a right side view thereof;
 FIG. 6 is a top view thereof;
 FIG. 7 is a bottom view thereof; and,
 FIG. 8 is a rear perspective view thereof.
 The details shown in broken lines form no part of the claimed design.

1 Claim, 6 Drawing Sheets(56)
